United States Patent Office.

ROBERT ROBSON, OF BUFFALO, NEW YORK.

Letters Patent No. 76,946, dated April 21, 1868.

IMPROVED BRICK-KILN.

The Schedule referred to in these Letters Patent and making part of the same.

TO ALL WHOM IT MAY CONCERN:

Be it known that I, ROBERT ROBSON, of the city of Buffalo, in the county of Erie, and State of New York, have invented a new and improved Brick and Tile-Kiln; and I do hereby declare that the following is a full and exact description thereof, reference being had to the accompanying drawings, in which—

Figure I is a partial plan and horizontal section of my improved kiln, showing compartments C D in plan, A F in section, line $z z$, and the remainder in section on line $z' z'$ of Fig. IV.

Figure II is a side elevation thereof.

Figure III is a vertical section of one of the divisions of the kiln, made in plane of line $x x$, Fig. IV, showing the inner end of the compartment.

Figure IV is a vertical section of the same cut by a radial plane, as shown by dotted line $y y$, Fig. I.

Like letters of reference designate corresponding parts in all the figures.

My invention consists—

First, in arranging a series of kilns, so as to leave an open area or space at the centre, with one or more passage-ways leading thereto, for supplying and removing the brick from the kilns.

Second, in the construction of the kilns with chimneys at their top, controlled by dampers, and arranging them side by side, with their furnace-ends contiguous, and their back ends communicating with each other by means of a flue provided with dampers, so that the products of combustion from the burning kiln are conducted to and used in the proximate one in drying the brick before their escape from the top thereof, the said kilns being burned successively, all as hereinafter more fully set forth.

As illustrated by the drawings, my improved kiln is constructed of a series of compartments or lesser kilns arranged in a circle, and designated by letters A, B, C, D, E, and F, leaving an open space or area, G, at the centre for affording access to the said compartments. H and I are passage-ways between the compartments on opposite sides of the kiln, for conveying the brick and tile to and from the kiln. The kiln is conveniently and economically constructed, with a contour of polygonal form, the various divisions being separated by radial partition-walls $m m$, as clearly shown in Fig. I.

Each of the compartments A B, &c., is provided with a suitable number of furnaces, $n n$, having doors or apertures $o o$, for the introduction of the fuel. These furnaces are separated from the main compartment by a wall, p , extending nearly to the top, but leaving sufficient space above for the passage of the products of combustion into said compartment, as clearly shown at q by black arrow, Fig. IV.

The inner end of each compartment of the kiln, and also of the passages H I, are provided at the bottom with a continuous flue, J, by which all are connected, and a free passage from one to the other obtained, as may be required. This flue is provided with dampers a, b, c, d, e, f, g, h between each division, by which the flue can be closed so as to leave an open passage only between such flues, as occasion may require. Apertures $r r$ are formed in the wall, separating the flue from the compartments, through which the products of combustion are permitted to pass, in a manner presently to be explained.

The top of each of the lesser kilns is constructed with one or more apertures or chimneys, $s s$, controlled by dampers u , for the final escape of the products of combustion, and the vapor arising from the drying bricks.

The operation of my improvements, constructed as above described, is as follows:

The bricks, tile, or other articles to be burned are supplied to the different kilns through one of the passages H I, and the central space G, and are arranged therein in any suitable manner.

Fire is now made in the furnaces of one of the kilns, A, for instance, and the chimneys of the same closed, while those of the next kiln, B, are left open. The dampers $a c$ being shut, and the damper b controlling the flue between the kilns being open, the products of combustion rising from the furnaces in A to the top of the kiln, descend among the brick, and pass into the flue J through apertures $r r$, and thence out into compartment B, from whence they escape through the openings $s s$ at the top, as clearly shown in Figs. I and IV, the black

arrows in the latter figure being supposed to show the direction of the draught through A, and the red arrows the course it takes through B.

After the kiln A has become sufficiently burned, the dampers *b* and *d* are closed and damper *c* opened, while the escape-passages *s* at the top of B are closed, and the similar ones in kiln C opened. Fire is then kindled in the furnaces of B, when the now properly dried bricks are ready for burning, the products of combustion passing into kiln C, (as shown by red arrows, Fig. I,) and thence escaping at the top in the same manner as from B when burning the kiln A.

The kiln A, after it has been burned, is kept closed for about a day, so as to allow it to gradually cool, when the damper *b* is again opened, which permits the hot air therein to escape with the products of combustion from kiln B into kiln C, and thus be utilized in drying the material in the latter. After the escape of the heated air, the damper *b* is a second time closed, and the dampers in the chimneys of A opened, when the cooling of the kiln is completed. The before-described operation is repeated in succession with the different kilns, the brick from the burned kilns being removed through the area *G* and delivery-passage as they become cold, and their place supplied with unburnt brick, so as to be ready for drying and burning in their proper turn.

It is manifest that by this means the kiln may be kept burning an indefinite period of time.

The number and arrangement of the lesser kilns may be varied, providing the necessary communication with each other is maintained by means of the continuous flue *J*.

The advantages of my improvements are as follows:

The construction and arrangement of the furnaces, flue, and chimneys are such that the products of combustion are distributed so as to prevent an excessive heating of any portion of the contents of the kiln.

The arrangement for conducting the products of combustion from one kiln to another effects a great saving in fuel, as the products of combustion are compelled to pass down through the contents of one kiln and up through the undried contents of the other before it can escape, by which the greater part of the heat is absorbed and utilized.

The dampers in the flue *J* and chimneys enable the direction and intensity of the draught to be perfectly controlled and regulated.

The general arrangement of the whole kiln is such as renders it simple and comparatively cheap of construction, easy of access in supplying and delivering the brick or tile, while the burning of the same is effected in a uniform and complete manner.

Another great advantage results from the draught passing through each kiln in contrary directions, first entering at the bottom in drying the brick, which heats the lower portion the hottest, and, secondly, by entering at the top in burning, equalizes the effect, by its greater action on the brick in the upper portion.

What I claim as my invention, and desire to secure by Letters Patent, is—

1. The combination and arrangement of a series of kilns, A, B, C, &c., with a central area, *G*, and passage-way or ways *H*, *I*, for supplying and removing the bricks and tile, substantially in the manner set forth.
2. I also claim the furnaces *n*, bridge-wall *p*, and connecting-flue *J* and chimneys *S*, arranged substantially as herein described.

ROBERT ROBSON.
